UNITED STATES PATENT OFFICE.

ALANSON H. BALES, OF GLEN ELDER, KANSAS, ASSIGNOR OF ONE-HALF TO
JOHN C. KROLL, OF FAIRBURY, NEBRASKA.

FRUIT-PRESS.

SPECIFICATION forming part of Letters Patent No. 605,267, dated June 7, 1898.

Application filed October 22, 1897. Serial No. 656,032. (No model.)

To all whom it may concern:

Be it known that I, ALANSON H. BALES, a citizen of the United States, and a resident of Glen Elder, Mitchell county, State of Kansas, have invented certain new and useful Improvements in Fruit-Presses; and my preferred manner of carrying out the invention is set forth in the following full, clear, and exact description, terminating with claims 10 particularly specifying the novelty.

This invention relates to presses, and more especially to that class thereof which are used for expressing juice or the like by means of a plunger and lever; and the object of the same 15 is to effect certain improvements in machines of this character.

To this end the invention consists in a peculiar construction of parts, all as herein after more fully set forth and claimed, and as 20 illustrated in the accompanying drawings, in which—

Figure 1 is a general perspective view of the machine complete. Fig. 2 is a central longitudinal section. Fig. 3 is a detail of the 25 bail and one end of the base and one extremity of the main lever. Fig. 4 is a detail of the follower. Fig. 5 is a cross-section of the stand, showing a longitudinal section of the chute.

Referring to the accompanying drawings, the numeral 1 designates the base, which is adapted to be mounted on legs or may be secured to and upon an ordinary table by means of the usual screw-clamps 2, and one end of this base is reduced in width, as at 3, and provided with holes 4 in its side.

5, Fig. 3, designates a bail of inverted-V shape, the lower ends of whose side arms are turned inward, as at 6, and are capable of being sprung into the holes 4 in the edges of the narrow part of the base, while its angle or bend 7 is adapted to enter a notch 8, formed in the upper side near one end of a main lever 9, and to be held therein by a button 10.

45 The numeral 11 designates a stand, which comprises a flat portion provided with a central aperture 12, two downturned ends 13, and two outturned feet 14, secured upon the base by screws or otherwise, and into the aperture 12 is seated the cylinder 15, which comprises an upright cylindrical body whose top 16 is

flaring and whose bottom 17 is tapering downward, and a circular strainer 18, seated within the body and interchangeable with another strainer of coarser or finer mesh. The cylinder has side hooks 19, extending outward and downward and adapted to enter eyes 20 in the ends of the stand, whereby it is held in proper position when in place. This cylinder may be of metal, such as galvanized iron, while the base can be of wood and the stand of either, though preferably also of metal, and all parts can be readily cleansed when it becomes necessary. It will be unnecessary to illustrate strainers of different 60 mesh from that shown herein.

The numeral 21, Fig. 4, designates the body of the follower, which has a round flat bottom 22, ribbed on its under side, as shown, and grooved around its edge, and within this 70 groove is fastened a packing consisting of wicking or other suitable substance 22', so that the follower shall fit the cylinder to prevent the juices of the fruit from rising therein when pressure is applied.

75 23 is the handle rigidly secured to the follower.

24 is a bolt passing through a clevis 25, secured on the handle 23 by pins, screws, or a cross-bolt 24', and thence upward loosely 80 through the lever 9, by which construction the lever may be moved to give the follower a vertically - reciprocating motion, and the handle moved meanwhile to turn it axially, so that the ribs on its bottom will be brought 85 over all parts of the fruit resting on the strainer 18, the pivoted bail 5 permitting such movement and also allowing the lever to be thrown completely back when desired to withdraw the follower completely from the cylinder. At such times the flaring upper end 16 of the cylinder will catch the drippings from the follower, as will be clear.

The numeral 30 designates a supporting-bar secured across within the stand, as shown, 95 and 31 is a chute resting at its upper end on such bar, with its body inclined downward toward and out the other side of the stand.

32 are raised sides at the edges of the chute, and 33 is its contracted mouth for delivery of 100 the juices expressed into a suitable vessel.

All parts are of the proper or preferred ma-

terials, proportions, and sizes, and considerable change in and addition to the details of construction may be made without departing from the spirit of my invention.

5 In operation, the parts being assembled as shown, the fruit to be treated is placed within the cylinder and the lever and follower brought down upon it. The handle end of the lever is then reciprocated vertically, which 10 gives a pounding action to the follower, while the handle 23 is reciprocated horizontally meanwhile, which turns the follower on its swivel, so as to bring all parts of its ribbed bottom over the fruit. The juices of the latter are thus forced out by the squeezing action between the ribbed bottom and the strainer, through which they pass, and flowing through the tapering lower end of the cylinder they fall onto the chute and are thence 15 conveyed into a suitable receiving vessel. From time to time the lever is thrown back, which carries the follower upward out of the cylinder and leaves the latter clear for the removal of pulp and insertion of new fruit, 20 and when the operation is completed all parts may be separated for suitable cleansing, as 25 well as for repair when necessary.

What is claimed as new is—

1. In a fruit-press, the combination with a base, a cylinder thereon having an interior strainer, and a follower working within the cylinder; of an A-shaped bail having inturned feet entering holes in and pivotally connected with the base, a lever having a notch in its upper side at one end for the reception of the angle of said bail, a swivel connection between the follower and the lever near the center of the latter, and a button on the lever adapted to be turned over said angle 30 when the bail is in place, as and for the purpose set forth.
2. In a fruit-press, the combination with a flat base with suitable supports, a main lever pivotally connected to the base, and a follower carried by the lever; of a stand comprising a flat body with a hole therethrough, two upright ends, and two feet attached to the base, a cylinder having a contracted lower end mounted within the hole in the stand its 35

body receiving the follower and its upper end 50 being flaring, a hook-and-eye connection between the cylinder and stand, a supporting bar across within the stand, and a chute resting at its upper end on said bar and having an inclined body with raised edges and contracted delivery end passing out from the stand, as and for the purpose set forth.

55 3. In a fruit-press, the combination with a follower, comprising an upright body, a round flat bottom, ribs on the under side thereof, and packing seated in a groove around its edge, and means for giving it a vertically-reciprocating motion and an axially-rotating motion; of an upright cylinder comprising a truly cylindrical body, a flaring upper end, 60 and a contracted or tapering lower end, and a strainer removably inserted within the cylinder-body and resting on said lower end thereof, as and for the purpose set forth.

65 4. In a fruit-press, the combination with a stand, a cylinder carried thereby and containing a strainer, a main lever extending across the upper end of the cylinder, and connections between the stand and one end of the lever; of a follower within the cylinder, a handle rigidly attached to the upper end of the follower, and a swivel connection between the handle and lever, as and for the purpose set forth.

70 5. In a fruit-press, the combination with a stand comprising a flat body with an aperture therethrough, and downturned ends, and eyes on such ends; of a support for the stand, a main lever pivotally connected with the support, a follower carried by said lever, a cylinder mounted within the aperture in the stand and receiving the follower, and hooks 75 projecting from the cylinder and adapted to enter said eyes, as and for the purpose set forth.

90 In testimony whereof I have hereunto subscribed my signature on this the 22d day of September, A. D. 1897.

ALANSON H. BALES.
